UNITED STATES PATENT OFFICE

168,873

FISHING LURE

Aaron Ernest Woolfe, Miami Beach, Fla.

Application August 22, 1952, Serial No. 21,157

Term of patent 14 years

(Cl. D31—4)

To all whom it may concern:

Be it known that I, Aaron Ernest Woolfe, a citizen of the United States of America, residing at the city of Miami Beach, county of Dade, State of Florida, have invented a new, original, and ornamental Design for a Fishing Lure, of which the following is a specification, reference being had to the accompanying drawing, forming a part thereof, and wherein:

Figure 1 is a bottom view of a fishing lure, showing my new design.

Figure 2 is a side view thereof.

Figure 3 is a top view thereof.

Figure 4 is a front view thereof.

I claim:

The ornamental design for a fishing lure, as shown.

AARON ERNEST WOOLFE.
